UNITED STATES PATENT OFFICE.

ISHAM P. WALKER, OF TYLER, TEXAS.

BUILDING CONSTRUCTION.

1,396,543.

Specification of Letters Patent.

Patented Nov. 8, 1921.

Application filed November 19, 1918. Serial No. 263,148.

To all whom it may concern:

Be it known that I, ISHAM P. WALKER, a citizen of the United States, residing at Tyler, in the county of Smith and State of Texas, have invented a new and useful Building Construction, of which the following is a specification.

This invention has reference to building construction, and its object is to improve and cheapen the construction of buildings and facilitate the erection thereof.

In accordance with the invention, the framework of the building is erected upon a suitable foundation and then interlocking slabs or tiles are secured to the framework to form an outer covering or sheathing for the building. The slabs or tiles may have their outer faces simulate brick or stone, or other material ordinarily used in building construction, and where the slabs join the interlocking arrangement is such as to shed water so that no water is admitted at the joints to the interior of the building, even though cementing material be omitted at the joints.

The invention also includes a joint construction for window and door frames and the like, whereby such frames are held in place without other fastening means than the slabs or tiles forming the outer sheathing of the building. Provision is also made for fastening the slabs or tiles to the framework in a manner permitting the rapid assembly of parts, whereby the rapidity of erection of the building may be greatly increased, permitting buildings constructed in accordance with the invention to be completed in but a fraction of the time needed for the erection of buildings employing brick or stone for the purpose.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

In the drawings:—

Figure 1 is a perspective view of a small portion of a building constructed in accordance with the invention, certain parts of the

exterior walls being omitted to disclose the framework.

Fig. 2 is a section on the line 2—2 of Fig. 1, but drawn on a larger scale. 60

Fig. 3 is a section on the line 3—3 of Fig. 2.

Fig. 4 is a section on the line 4—4 of Fig. 1.

Fig. 5 is a rear face view of the framework at a window opening, such as seen in Fig. 1. 65

Fig. 6 is a perspective view of a portion of a window frame and adjacent slabs or tiles, with the parts separated to better show 70 the construction.

Fig. 7 is a perspective view, as seen from the rear, of one of the slabs or tiles adjacent to a window or door frame.

Fig. 8 is a top plan view of the window 75 frame and cap plate or water table thereon.

Fig. 9 is a top plan view of the sill beneath the window frame.

Referring to the drawings, there is shown a base or foundation 1 which may be made 80 of concrete or any other suitable material, and extending lengthwise of the upper surface of the base is a rib 2 having an upright shoulder 3 on the side toward the interior of the building and an inclined face 85 4 on the side toward the exterior of the building (Fig. 3).

Erected on the foundation is a framework consisting of corner posts 6, studding 7, battens or strips 8 connecting the corner 90 posts, and studding braces 9, of which only two are shown in Fig. 1 but it is to be understood that the braces are used wherever necessary.

The foundation 1 and the framework 95 erected thereon constitute a support for an exterior wall or sheathing made up of slabs or tiles 11, 12, 13, 14, 15, 16, 17, and 18 differing in size or some other characteristic but all having common characteristics. The 100 various forms of slabs or tiles are only those indicated in a building constructed in accordance with the showing of Fig. 1. Other buildings may need certain changes in the forms of the slabs or tiles but those 105 characteristics which are common to the different slabs illustrated in Fig. 1 will still be common to said other forms necessitated by variations in the shape of the building.

The slabs 11 and 12 are of generally rectangular form with the slabs 12 half the length of the slabs 11 and both may be of

the same height. The size of the slabs represent in face area a group of several ordinary bricks or a building stone and may be readily molded into shape from concrete or 5 the like with the exposed face having markings 19 thereon, shown in the drawings as outlining ordinary brick. The slabs or tiles 11 and 12 differ from each other in that the slabs 11 may be twice the length of the slabs 10 12 in order that, in the finished building, the joints may be properly broken. Most of the slabs, however, will be long slabs like the slabs 11 and certain of the slabs, especially those adjacent to openings in the wall 15 and at corners, have special formations as will hereinafter appear.

Each slab is provided at the bottom edge with a longitudinal groove 20 and at the top with a longitudinal rib or tongue 21, the rib 20 21 having the same shape as the rib 2 on the foundation and the grooves 20 being shaped to snugly receive the ribs or tongues 21. At one end of each block 11 or 12 is an upright groove 22 and at the other end of the block 25 is an upright rib or tongue 23 shaped to snugly fit into the groove 22. The upright grooves 22 and corresponding ribs 23 differ from the grooves and tongues on the tops and bottoms of the blocks in that, while 30 of triangular cross section, the flat wall or shoulder and the inclined face or shoulder are oppositely disposed from the arrangement of the ribs 2, that is, there is a flat shoulder 3^a toward the outer face of the wall and an inclined shoulder 4^a toward the inner face of the wall (Fig. 2).

The tongues and grooves at the tops and bottoms of the blocks are horizontal in the finished walls while those at the ends of the blocks are upright. In the completed 40 building there is a liability of water, in case of storms, finding its way to the tongues and grooves and in such event the water will simply flow down the inclined walls of the tongues toward the exterior of the wall of the building, but in the upright tongues at the ends of the blocks the water will simply flow lengthwise of the tongues until it reaches the bottom of a block where the inclined wall of the tongue will direct 45 the water outwardly. At the same time the opposite inclination of the tongues and grooves at the top and bottom of a block and at the ends of the block tends to improve the interlocking of the blocks together.

Each slab or tile wherever located and however constructed is formed on the inner face at the upper edge with an ear or ears 60 24, the longer slabs having an ear near each end and the shorter slabs having an ear near the middle, although such disposition of the ears is not obligatory. Each ear, which projects laterally from the inner face of the respective slab, has a 65 perforation 25 and the ear is of such length

in a direction away from the block that it will override and rest upon a respective one of the battens 8 which are so spaced apart in the direction of the height of the building as to sustain some of the weight 70 of the slab when applied to the batten. Each perforation 25 in an ear 24 is traversed by a nail or pin 26 entering the corresponding batten 8 being either driven into the batten during the construction of the building or entering a socket or passage formed in the batten for the purpose. An ordinary wire nail of suitable size answers very well for the pin 26.

In constructing the building, the foundation is first laid and allowed to harden. Such foundation, if made of concrete, is readily formed by first building a suitable mold, as is customary in the formation of foundations from plastic material. Of 85 course the foundation might be made of bricks or other building material but the use of concrete molded into shape during the process of building is advantageous.

After the foundation is finished and set 90 and the molds removed, the framework is constructed in a manner familiar to carpenters, and hence needs no particular description.

After the framework is up the lowermost 95 course of slabs is laid with the ears 24 resting on the lowermost series of battens all of which support the slabs through the ears to some extent. The bottoms of the slabs also rest upon the foundation 1 with the bottom 100 grooves 20 receiving the ribs or tongues 2 and the meeting ends of the slabs having the upright ribs 23 entering the grooves 22. The various slabs of the lowermost course are therefore locked together and to the foundation 105 and held to the framework by the ears 24 resting on the battens 8 and secured thereto by the pins 26. The succeeding courses are laid in the same manner as brick or stonework, and, while cement may be employed at the meeting edges of the slabs, such material is not necessary, especially where the structure is properly built. Care, however, is taken to break joints after the manner of ordinary brick and stonework, 110 and in Fig. 1, such joints are shown by relatively heavy lines 27. These lines do not 115 prominently appear in the finished building but are shown exaggerated in Fig. 1 to make it appear where the joints may occur.

Of course a building is assumed to have suitable openings, and corners necessarily occur at different points. Such openings or corners necessitate some modifications in the forms of the slabs or tiles making up the 125 outer wall of the building.

In Fig. 1, there is shown a window opening 28, this opening also appearing in some others of the figures. The opening 28 contains a window frame 29 which, in the main, 130

may correspond to ordinary window frames with side members 30, a top 31 and a sill 32.

The invention contemplates the use of another sill 33 and a cap or water table 34, 5 both of which as well as the adjacent edges of the slabs or tiles are shaped to fit and interlock.

The window frame may, as is customary, be made of wood and may follow the usual 10 practice in this construction. The top 31 of the window frame is formed with a tongue 35, of triangular or similar cross section, fitting in a groove 36 in the underface of the water table 34 and the water table is 15 provided with a longitudinal tongue 37 on its upper face to enter the bottom groove of a slab or slabs extending across the top of the window opening. The cap or water table is longer than the width of the window 20 frame and the corresponding slab or tile 18^a has a corner notch or recess 38 suitably shaped to receive the overhang of the water table 34. The recess 38 is provided with a tongue 39 and the overhang of the water 25 table has a groove 40 in the overhang portion to receive the tongue 39, thereby interlocking the water table and the adjacent slab 18^a at each end of the water table and side of the window opening.

30 The sill 33 where underriding the window frame sill 32 is provided with a tongue 41 entering a corresponding groove 42 in the bottom of the sill 32. The ends of the sill 33 project beyond the sides of the window 35 frame, entering a suitable recess 43 in the adjacent slab 18. The recess 43 has a triangular or other suitably shaped upright groove 44 therein and the sill 33 is provided with a triangular or similarly shaped tongue 40 45 to enter the groove 43 when the projecting end of the sill is lodged in the recess 43.

Each tile or slab 17, 18 and 18^a at the end 45 bordering the opening 28 has a laterally extended offset 46 forming a facing of suitable depth for the opening 28 so that the window frame may be inset with relation to the outer wall of the building, thus producing an appropriate finish. The inner edge 50 of the offset 46 has an upright groove 47 formed therein to receive an upright tongue 48 on the corresponding side member of the window frame and of undercut or dovetail cross section, whereby the tongue 48 when seated in the groove 47 serves to lock the

55 window frame in place in the wall at the sides of the window frame while the cap or water table 34 and sill 33 serve to lock the top and bottom of the window frame in the window opening. The sill 33 is provided on 60 the bottom edge with a groove 49 to receive the tongue 21 of the slab or slabs immediately beneath the sill 33.

If the window frame be of the box type the tongues 48 are made fast to the outside 65 of the boxing instead of directly to the sides

of the window, as shown in the drawings, otherwise the structure may be as illustrated. In the case of door frames, the structure may be similar to that shown with respect to window frames, except that the sill 32 is 70 not used.

Where corners are present, the slabs or tiles 13 to 16 are of similar construction to the slabs 11 and 12, except that the meeting edges are beveled as indicated at 50 in Figs. 75 1 and 2, and the beveled edge of one of the meeting corner blocks is provided with an upright tongue and the other block with an upright groove to receive the tongue, the same as the upright meeting edges of other 80 blocks. The grooves and tongues of the beveled edges of the corner blocks are indicated in Fig. 2 at 22^a and 23^a respectively, otherwise the corner blocks may be of the same construction as the blocks 11 and 12. 85

In Figs. 1 and 2 the corner blocks are of a form in which the corner is a right angle projecting corner. In the case of a right angle or other inset corner the bevel will be the reverse of that shown in Figs. 1 and 2 90 and the bevel will correspond to the angle to be produced. It will be understood that the bevels of the corner blocks will correspond to the angle to be produced in each instance, and the same general construction 95 may apply to curved or other shaped blocks for building walls of like conformation.

The invention is not confined to any particular size or shape of slab or tile for the siding, or to the imitation of brick or stone, 100 since for some purposes the slabs may be perfectly plain on the exterior. A convenient size for handling and for rapid building may be about twenty-four inches long and twelve inches wide and one and one-half 105 inches thick, but these particular dimensions are by no means obligatory. The smaller slabs agree in dimensions with the larger slabs except that they may be twelve inches square and one and one-half inches thick. 110

The cap plate or water table may be cast in one piece or may be made up of two or more pieces.

What is claimed is:—

1. In building construction, a foundation 115 having a rib or tongue on its upper surface extending about the foundation, said rib or tongue being right triangular in cross section and having a vertical wall facing inwardly with respect to the building and a 120 slanting wall facing outwardly, and a series of slabs laid in courses, each slab having means for interlocking with adjacent slabs on all edges, said means comprising a groove on its lower edge and along one side edge, 125 and a tongue or rib on its upper edge and along the other side edge, the grooves being designed to receive the tongues or ribs and the latter being shaped similarly to the tongue or rib on the foundation, the founda- 130

tion rib interlocking with the lowermost course of slabs and all the ribs and grooves extending intermediate the outer and inner faces of the slabs, the tongues on the upper edges of the slabs having their vertical walls facing inwardly while the tongues on the side edges have their vertical walls facing outwardly.

2. In building construction, an outer wall 10 comprising slabs or tiles laid in courses with each tile having a tongue and a groove at the respective top and bottom edges and the tiles having matching tongues and grooves at the respective side meeting edges, 15 the tongues on the top edges having their outer faces slanting and their inner faces vertical, and the tongues on the side edges having the outer faces parallel to the face of the wall and the inner faces at an angle 20 to the wall, all of the tongues and grooves extending throughout the length of the edge on which they are provided and intermediate the outer and inner faces of the slabs.

3. In building construction, a slab or tile 25 constituting an element of the outer wall of the building, said slab having its upper edge provided with a longitudinal tongue, said tongue having its rear face upright and its front face slanting downwardly and forwardly from said upright rear face, and the bottom edge of the slab having a longitudinal groove with its rear wall upright and its front wall slanting forwardly and downwardly from the upright rear wall, whereby 30 the matching upper and lower edges of adjacent slabs prevent outward movement of said slabs, each slab having its side edges provided with respective tongues and grooves where meeting other slabs so as to 35 lock with said slabs against movement inwardly, all of said tongues and grooves extending continuously for the length of the edge on which they are provided.

4. In building construction, a slab or tile 45 constituting an element of the outer wall of the building, said slab having its upper edge provided with a longitudinal tongue with the rear face of the tongue upright and the front face thereof slanting downwardly and forwardly from said upright rear face, the bottom edge of the slab having a longitudinal groove with its rear wall upright and its front wall slanting forwardly and downwardly from said upright rear wall, the 50 side edges of the slab having respective tongues and grooves where meeting other slabs of like construction, and integral projecting means on the rear face of the slab adjacent the upper edge thereof and intermediate the ends for securing the slab to a 55 support.

5. In building construction, a foundation,

a framework including horizontal battens or strips erected upon the foundation, courses of tiles or slabs secured to said strips and supported partly thereby and partly by the foundation, an opening provided in the framework, a sill set in the opening and interlocking with the adjacent tiles or slabs at its bottom and ends, a water table also set in the opening and interlocking with the adjacent tiles or slabs at its top and ends, a frame set in the opening between the sill and water table and interlocked with both parts, each of the tiles or slabs interlocking 75 with those slabs adjacent it, and the tiles or slabs adjacent the frame having offsets interlocking therewith.

6. In building construction, a framework provided with an opening, a frame adapted 80 to the opening, a water-table cap plate on top of the frame in the opening, and interlocking tiles or slabs constituting the outer wall of the building, certain of said slabs having recesses for receiving the ends of the 85 cap plate, and the cap plate, frame and slabs being of interlocking tongue and groove construction.

7. In building construction, a framework provided with an opening, a frame adapted 90 to the opening, a water-table cap plate on top of the frame in the opening, and interlocking tiles or slabs constituting the outer wall of the building, certain of said slabs having recesses for receiving the ends of 95 the cap plate, and the cap plate, frame and slabs being of interlocking tongue and groove construction, those slabs or tiles at the sides of the opening having the edges adjacent thereto provided with inward continuations or offsets to inset the frame in the opening.

8. In building construction, a framework having a window opening therein, a window frame lodged in the opening, a cap plate and sill for the window frame each projecting beyond the side edges of the window frame, and slabs or tiles constituting elements of the outer wall of the building, the slabs having edge recesses to receive the ends of 105 the cap plate and sill, the slabs, cap plate and sill having interlocking tongues and grooves where meeting, and the slabs where adjacent to the window frame having angle extensions with said angle extensions and 110 the window frame provided with interlocking tongues and grooves.

In testimony that I claim the foregoing as my own, I have hereto affixed my signature
